UNITED STATES PATENT OFFICE.

JAMES H. WEAVER, OF CHICAGO, ILLINOIS.

ENVELOPE.

SPECIFICATION forming part of Letters Patent No. 286,881, dated October 16, 1883.

Application filed March 24, 1882. (Model.)

To all whom it may concern:

Be it known that I, JAMES H. WEAVER, of Chicago, in the county of Cook and State of Illinois, have invented certain new and useful 5 Improvements in Envelopes, of which the following, in connection with the accompanying drawings, is a specification.

In the drawings, Figure 1 is a perspective of an envelope or packet embodying my invention. Fig. 2 is a face view of the blank, and also indicates the mode of cutting it from the sheets. Fig. 3 is a vertical central cross-section of the completed envelope or packet; and Fig. 4 and 5 are perspectives showing 15 slight modifications of construction.

Like letters of reference indicate like parts.

The object of my invention is to make a seamless envelope or packet which may be fastened or closed securely enough to contain the contents with certainty, and which, without being unfastened, may be so manipulated as to expose the contents to view.

In the drawings, A represents a blank or sheet cut in form for being folded to produce one of my envelopes or packets. The broken lines $a\ a\ a\ a$ indicate where the blank is to be folded. Four leaves or wings, $a'\ a'$ and $a''\ a''$, are thus formed. Between these leaves are the notches $b\ b$, and the corners of the leaves 3c are beveled, as shown. These beveled parts or edges of the smaller leaves a'' are pointed and meet each other. The leaves $a'\ a'$ are not so pointed as the leaves $a''\ a''$, and are longer than those, which are as shown. I paint a coat 35 of mucilage along the outer edge or end of one of the leaves $a'\ a'$, as shown at c , and allow the mucilage to become dry before folding the envelope. This blank, when folded, will make an oblong envelope, as shown in Fig. 1. To finish 40 the envelope I simply fold it along the lines indicated, but do not fasten or seal it at any part until I have use for it. I then lay back or unfold the flaps or wings, and arrange the material to be inclosed in such position that it will 45 be covered when the flaps are again folded. The end flaps or wings, $a''\ a''$, are short enough not to lap each other when folded in, and are folded in first. The flaps or wings $a'\ a'$ are broad enough to overlap each other when folded 50 in, and are folded in last, thus inclosing the flaps or wings $a''\ a''$. The contents will be securely confined in the folded envelope or packet by

simply moistening the dry mucilage and pressing it down upon the opposite flap or wing, to which it will adhere, thus connecting the two outer flaps or wings together. This connection, however, leaves the envelope or packet in such condition that, by merely pinching or pressing in its longitudinal edges, it will be spread apart or opened enough to admit of the contents 60 being viewed by looking in at the end of the packet, the contents not being wholly covered by the interior flaps or wings, and the outer wings being then arched up above the contents and interior wings, as indicated in Fig. 65 3. At the same time the contents are retained in the packet. A great variety of goods may thus be mailed in these packages, and the goods or contents may be viewed by the postmasters without breaking the packages for that purpose. The expense and inconvenience, therefore, of shipping goods by mail is much diminished. 70

In Fig. 4 I have shown a modification of construction, which consists merely in gumming 75 the longitudinal edges of both wings $a'\ a'$, one being gummed on one side, as indicated in Figs. 2 and 4, and the other on the other or opposite side, as shown at c in Fig. 4. I also perforate the upper wing along the edge of its 80 gummed portion, as shown at c' . By this means the address of the consignee may be written, as usual, on one side of the package and the address of the consignor on the other. The package may be easily unsealed by the 85 consignee by breaking it open along the line c'' , when the contents may be removed. The integrity of the envelope, however, is not thereby destroyed, but may be folded reversely and again sealed, as if gummed only as shown in Fig. 2, 90 thus bringing the address of the consignee on the outside. In other words, the modification shown in Fig. 3 makes the envelope a return package without destroying its identity and without material change in construction. The 95 gummed portion of one gummed wing overlaps or lies beyond the gummed portion of its fellow when the envelope is folded for being sealed, as will be perceived, each of such wings then overlapping the central longitudinal line of the body or part between the leaves. 100

In Fig. 5 I have shown a modification of construction, the modification consisting in slitting or slotting one of the wings or flaps $a'\ a'$

longitudinally, as shown at *d*, to admit of the packet being fastened by slipping the other wing or flap *a'*, into the slot *d*, instead of employing mucilage for fastening the wings or flaps together. A large class of goods will be securely enough held by means of this slotted fastening.

In cutting out the blanks I so cut the sheets that the pointed wings or flaps *a'' a''* will coincide with the corners of the sheets, or come from corresponding parts of the sheet, as indicated in Fig. 2. By this means I find that there is much saving in material, for if the blanks were so cut that a line passing longitudinally through them would be at right angles to the edges of the sheet from which the blanks were cut there would be much more waste.

It is not essential that the notches *b b* should be cut, as the paper may be folded, as described, when no notches are so made. The loose or ungummed flaps or wings may also be drawn

out and replaced, in order that the contents may be viewed, and again confined.

Having thus described my invention, what I claim as new, and desire to secure by Letters Patent, is—

A return envelope or packet, made of paper, and consisting of a central portion or body having thereon two opposite wings or flaps, *a' a'*, adapted to overlap each other, and also two opposite wings or flaps, *a'' a''*, the wings *a' a'* being gummed on opposite sides, respectively, along their edges, whereby the said envelope or packet, after being once sealed, and after having its seal broken, may be again sealed and utilized by having its flaps folded in the opposite or reverse direction from that in which they were first folded, substantially as and for the purposes specified.

JAMES H. WEAVER.
